CLAIM

The ornamental design for a hair dryer, as shown and described.

DESCRIPTION

FIG. 1 is a front perspective view of my new design for a hair dryer.

FIG. 2 is a left side elevation view of FIG. 1.

FIG. 3 is a right side elevation view of FIG. 1.

FIG. 4 is a front side elevation view of FIG. 1.

FIG. 5 is a rear side elevation view of FIG. 1.

FIG. 6 is a top plan view of FIG. 1.

FIG. 7 is a bottom plan view of FIG. 1.

FIG. 8 is a front perspective view of my new design for a hair dryer. The buttons shown in dotted lines are for illustrative purposes only and are not part of the claimed design.

FIG. 9 is a left side elevation view of FIG. 8.

FIG. 10 is right side elevation view of FIG. 8.

FIG. 11 is a front side elevation view of FIG. 8.

FIG. 12 is a bottom plan view of FIG. 8.

FIG. 13 is a front perspective view of an alternate embodiment of my new design for a hair dryer.

FIG. 14 is a left side elevation view of FIG. 13.

FIG. 15 is a right side elevation view of FIG. 13.

FIG. 16 is a front side elevation view of FIG. 13.

FIG. 17 is a rear side elevation view of FIG. 13.

FIG. 18 is a top plan view of FIG. 13.

FIG. 19 is a bottom plan view of FIG. 13.

FIG. 20 is a front perspective view of my new design for a hair dryer. The buttons shown in dotted lines are for illustrative purposes only and are not part of the claimed design.

FIG. 21 is right side elevation view of FIG. 20.

FIG. 22 is left side elevation view of FIG. 20.

FIG. 23 is a front side elevation view of FIG. 20; and,

FIG. 24 is a bottom plan view of FIG. 20.
